BOILER CASING

Filed Oct. 14, 1926

Fig. 1

UNITED STATES PATENT OFFICE

ISAAC HARTER, OF DONGAN HILLS, NEW YORK, ASSIGNOR TO THE BABCOCK & WILCOX COMPANY, OF BAYONNE, NEW JERSEY, A CORPORATION OF NEW JERSEY

BOILER CASING

Application filed October 14, 1926. Serial No. 141,661.

This invention relates to a casing for a boiler, and will be understood from the description and the accompanying drawing, in which Fig. 1 is a vertical section through a boiler in connection with which an embodiment of the invention is illustrated; Figs. 2 and 3 are similar sections on an enlarged scale, partly broken away; Fig. 4 is a section along the line 4—4 of Fig. 3 and Fig. 5 is a similar section of a modification.

In the drawing, reference characters 10 and 11 indicate upper and lower horizontally-disposed drums that are connected by banks of tubes 12. A pipe 13 extends from the drum 10 to the superheater 14 that is located between the tubes 12.

Supports 15 are provided beneath the sides of the boiler casing. The boiler casing may be made of tile, for example. The boiler casing rests upon the supports 15, and is provided with a top 16 and a bottom 17, with soot pockets 18 located in the bottom.

Longitudinally-disposed metal plates 20 are provided for the outside of the side walls of the casing, each one of these metal plates being preferably provided with flanges 21 along the edges thereof. Longitudinally-disposed stiffening members or girders 22 are bolted to the horizontal flanges 21 by means of the bolts 23, and keep the plates in place, the supporting members 22 being held in fixed position in any convenient manner. Channel-shaped tile 25 that may be made of metal or refractory material, make up the inside lining of the side walls of the casing. These tile have longitudinal projections thereon, such as ribs or flanges 26, that may contact with the outer portion of the boiler, here consisting of the outside row of tubes 12, as most clearly shown in Fig. 4.

Horizontally-disposed metal channel members 28 are located at intervals along the inside wall of the casing, and the flanges thereof contact with the corresponding flanges on the tile above and below the same. Soot blowers 29 may be located in the channel members 28. The space between the side walls, made up of metal plates 20 on one side, and the tile 25 and channels 28 on the other side, is filled with insulating material 30.

L-shaped bars 31 are riveted to the lowest of the metal plates 20 (Fig. 2), and are anchored to the walls 15 by means of anchor bolts 32, which are bolted to the L-shaped bars 31, and are seated in suitably shaped grooves provided in the topmost tile of the walls 15. Longitudinal baffles 32' are provided between the side walls of the casing and the drum 10 to prevent the hot gases from rising beyond the upper ends of the tubes 12.

In the modification shown in Fig. 5, the rows of tubes 12' are shown staggered and the tubes in the outside row extend into recesses 33 in the flanges or ribs 26 of the tile 25. In both illustrations of the invention, hot gases can pass between the outside rows of tubes 12 and the inside walls of the boiler casing, and are guided along horizontal paths by means of the flanges 26 of the tile. In this way, the outside rows of tubes next to the walls will have free circulation of hot gases on all sides thereof to cause greater heat absorption by these tubes than would be the case if ordinary flat tile were laid against the tubes 12. At the same time, the tubes 12 prevent the tile 25 of the furnace wall from falling inwardly.

Although the invention has been described in connection with a boiler in which an upper and lower horizontally-disposed drum is connected by vertically-disposed tubes with superheater tubes interposed, in which hot gases are to be passed horizontally among the tubes, it is to be understood that the invention may be used with other types of boilers.

I claim:

1. In combination, a boiler casing wall having an inner lining formed of horizontally disposed channel members with inwardly extending flanges, and a boiler having vertically disposed tubes and having its outer tubes contacting only in spots with the flanges of said members whereby said channels are held against inward lateral movement by said boiler.

2. In combination, a boiler casing wall having its outer surface formed of a plurality of plates secured together at adjacent edges, stiffening members secured between adjacent plates, a boiler having vertically disposed

- tubes within said casing, an inner lining for said casing formed of a plurality of tile in the shape of channels horizontally disposed with inwardly disposed flanges, said flanges contacting in spots with the outer portion of said tubes and the portions between flanges being spaced from the boiler, and a layer of insulating material disposed between said plates and said tile.
- 10 3. A boiler casing wall having its outer surface formed of a plurality of plates provided with flanges at their adjacent edges, stiffening members disposed between said flanges and secured thereto, an inner lining of metallic material an insulating material disposed between said plates and lining, a boiler having vertically disposed tubes within said casing and inwardly extending horizontally disposed projections on said lining contacting with tubes of said boiler within the casing with the portions of the lining between projections spaced from the boiler, whereby gases may circulate between said projections and contact with the outer portion of the boiler.
- 15 4. In a water tube boiler having vertically disposed tubes, a horizontally channeled casing for said boiler having the channels on the side toward said tubes and in proximity to some of said tubes.
- 20 5. In a water tube boiler having vertically disposed tubes, a horizontally channeled casing for said boiler having the channels on the side toward said tubes, the edges of the flanges of said channels contacting with some of said tubes.

ISAAC HARTER.
